APPARATUS FOR DISPENSING STRAWS

Charles W. Beamer, Mojave, Calif.

Application October 31, 1938, Serial No. 238,031

1 Claim. (Cl. 312—84)

My invention relates to improvements in apparatus for dispensing straws such as are used at soda fountains and the like.

The invention is designed with the particular purpose in view of providing an inexpensive sanitary apparatus for dispensing such straws one at a time from a source of supply and providing against the straws sticking together or becoming bent or otherwise damaged.

Another object is to provide apparatus for the purpose above set forth whereby the straws are dispersed in a position and manner such that handling of the ends of the straws is obviated when removing the same from the apparatus, so that said ends may be kept clean and sanitary for insertion in a drink or the mouth.

To the accomplishment of the foregoing, and the subordinate objects presently appearing, a preferred embodiment of my invention has been illustrated in the accompanying drawings, set forth in detail in the succeeding description and defined in the claim appended hereto.

In said drawings:

Figure 1 is a view in perspective of apparatus constructed in accordance with my invention.

Figure 2 is a view in front elevation.

Figure 3 is a view in transverse vertical section taken on the line 3—3 of Figure 2 looking in the direction indicated by the arrows.

Figure 4 is a view in end elevation.

Referring to the drawings by numerals, in the illustrated embodiment thereof, my improved dispensing apparatus comprises a casing 1 including a flat substantially rectangular bottom 2, similarly shaped ends 3 spaced apart a distance slightly greater than the length of the average straw, and a back 4 all formed in one piece and of suitable metal, the bottom 2 having a forwardly projecting ledge 5 and the ends 3 having lower front edge extensions 6 forming end closures for said ledge.

A pad 7 of suitable material, such as felt, may be cemented or otherwise secured to the under face of the bottom 2 for cushioning the casing on a counter, showcase, or the like.

The casing 1 has a top 8 and an upper front panel 9 both formed of rectangular plates of transparent material, such as glass, fitting endwise between the ends 3, the panel 9 fitting against the front edge of the top 8 and inclining downwardly and rearwardly for a purpose presently seen. The top 8 and panel 9 are secured to lateral internal flanges 10 extending from the ends 3 and to which said top and panel may be cemented or otherwise affixed.

Extending lengthwise between the ends 3 is an

elongated angular plate 11 of suitable metal including a top section 12 secured at its rear edge, as by soldering, to the back 4 at a suitable distance below the top 8 to extend forwardly and downwardly, and a front section 13 spaced in substantial parallelism from the panel 9 in the rear of the latter a distance somewhat greater than the outside diameter of the usual straw. The ends of section 13 as well as the ends of the section 12 are free and the section 13 has its lower edge extending slightly below the lower edge of the panel 9 all for a purpose presently seen.

As will be understood, the plate 11 forms together with the top 8 and panel 9 a hopper 14 in the upper part of the casing 1 having a forwardly sloping bottom and an open bottom chute 15 at the front of said hopper inclining downwardly and rearwardly, said chute and hopper extending clear across the casing 1 and having a transparent top and front. The back 4 terminates at the rear edge of the section 12 to provide a doorway for the introduction of straws into the hopper 14 and which has a closure flap 16, hinged, as at 17, to said back.

Below the mouth of the chute 15 is a dispensing reel comprising a horizontal shaft 18 journaled at its opposite ends in the ends 3 of said casing 1 parallel with the mouth of the chute 15 and directly below said mouth, and a pair of straw conveying discs 19 fast on said shaft adjacent opposite ends of the latter. The discs 19 are notched peripherally and correspondingly at equidistantly spaced points, as at 20, for the reception of opposite ends of a straw dropping through the mouth of the chute 15.

The spacing of the notches 20 is such that when a pair thereof is presented, by rotation of said discs 19 counter-clockwise as viewed in Figure 3, directly below the mouth of the chute 15 a preceding pair will be presented at the front of said discs above the transverse center of the latter. The discs 19 are so arranged that the peripheries thereof clear the lower edge of the panel 9 but the lower edge of section 13 projects slightly into each pair of notches 20 moved into registration with the mouth of the chute 15. By virtue of this arrangement, the lower edge of section 13 coacts with the rear walls of said pair of notches 20, presented below the mouth of the chute 15, to yieldingly block further rotation of said discs with the preceding pair of notches located above the transverse center of said discs in which position of said last pair a straw lying therein cannot fall out. As a further result of the

described relation of the notches 20 and section 13, each time a pair of notches 20 is rotated past the lower edge of section 13, said section is slightly vibrated, also the section 12, to loosen up the straws 22 in the hopper 14 and chute 15 and thereby obviate sticking of the straws, together, in said hopper and chute.

5 A comb plate 23 rising from the bottom 2 directly in front of the shaft 18 closes the bottom 10 of the casing 1 below the chute 15 and straddles the discs 19 so as to act as a stripper preventing sticking of the straws in the notches 20 when the latter are in substantially lowermost position.

15 Fast on one end of the shaft 18 is a ratchet wheel 24 adapted to be engaged by a spring pressed pawl 25 pivoted, as at 26, on an up-standing hand lever 27 loosely mounted on said shaft, the arrangement being such that under 20 forward movement of said lever and pawl, said wheel is operated to rotate said shaft in the direction previously indicated. A suitably connected coil spring 28 tensions the lever 27 against forward movement. A segmental guard 29 fast 25 on the appropriate end 3 of casing 1, and through which the hand lever 27 extends, establishes a normal rearward limit of movement of said lever 27 under the urge of spring 28 and limits forward movement of said lever so that each forward operation of the latter, within the prescribed limit, results in rotation of one pair of notches 28 out of registration with the mouth of the chute 15 and a succeeding pair into such registration.

30 As will now be seen, the straws 22 gravitate 35 down the bottom of the hopper 14 into the chute 15 in single file to drop one at a time into a pair of notches 20 of discs 19 registering with the mouth of the chute 15 for conveying forwardly by operation of the hand lever 27 into a position 40 such that they will not drop off the discs 19 and may be grasped between the ends thereof and removed. As will also be understood, in the rearward limit of movement of the lever 27, a pair of notches 20 is located in registration with 45 the mouth of said chute and each time a straw

is fed or conveyed forwardly the plate 11 is vibrated gently to loosen up the straws in the hopper and chute. The interior of the hopper 14 and chute 15 is always visible so that the condition of the supply in the hopper and chute 5 may be readily ascertained. The ledge 5 provides an open top trough for depositing of straws if desired.

The foregoing will, it is believed, suffice to 10 impart a clear understanding of my invention without further explanation.

Manifestly the invention, as described, is susceptible of modification without departing from the inventive concept and right is herein reserved to such modifications as fall within the 15 scope of the subjoined claim.

What I claim is:

In apparatus of the class described, a casing comprising back and end plates, respectively, an upper front plate extending between said end plates, an angular plate-like member enclosed by said plates and forming together therewith a straw containing hopper having a discharge chute extending along the bottom thereof in depending position, said member being mounted 20 on the back plate for vibration to agitate the straws in said hopper and chute and thereby facilitate discharge of said straws through said chute, and means for conveying the discharged straws forwardly from said chute for grasping 25 by the hand comprising a reel rotatably mounted in said end plates to extend along the bottom of said chute below the same and including a plurality of discs rotatable beneath said chute and peripherally notched to receive in the edges 30 thereof the discharged straws, said discs and notches being constructed and arranged to engage said member and intermittently vibrate the same under rotation of the reel, and a comb plate extending upwardly between said discs to 35 function as a stripper for removing straws from said notches sticking therein when the notches are rotated into substantially lowermost position.

CHARLES W. BEAMER.
